UNITED STATES PATENT OFFICE.

MICAJAH C. HENLEY, OF RICHMOND, INDIANA.

ROLLER-SKATE.

SPECIFICATION forming part of Letters Patent No. 319,712, dated June 9, 1885.

Application filed October 30, 1884. (No model.) Patented in Canada February 10, 1885, No. 21,069.

To all whom it may concern:

Be it known that I, MICAJAH C. HENLEY, of Richmond, in the county of Wayne and State of Indiana, have invented certain new and useful Improvements in Roller - Skates, of which the following is a specification.

My invention relates to roller-skates; and it consists in certain improvements upon the construction for which Letters Patent were granted to me bearing date August 23, 1881, and numbered 245,950.

In the annexed drawings, Figure 1 is a perspective view of the complete skate; Figs. 2 and 3, respectively, longitudinal and transverse sections through the truck-frame, showing the spring and compression devices; Fig. 4, a view of the bearing-plate and screw detached; Figs. 5, 6, and 7, views illustrating a modification.

The purpose of the present invention is to facilitate the adjustment of the spring or cushion by which the roller-axes and the sole-plates are caused to stand normally parallel, and to insure the retention of the adjusting devices in their proper positions when the skates are in use.

In the drawings, A represents the sole-plate of a skate of substantially the same design as in my former skate, referred to above, and which may be furnished with straps, clamps, or other suitable devices for securing it upon the shoe of the wearer.

Near each end there is secured to the under side of the sole-plate A a hanger-frame, B, having two arms, a and b, the inner arm being in each instance longer than the outer one, and each being provided with an eye or perforation, c.

C indicates a truck-frame, consisting of a central rectangular box or chamber, d, from which two perforated ears, e e, project outward and downward to receive the axle D, upon the ends of which are mounted the rollers E, as usual.

The box or chamber portion of the truck-frame C is formed with a teat or stud, f, on the outer face midway between the ends of the axle, as shown in Figs. 1 and 2 and in dotted lines in Fig. 3, and directly in line with the teat or stud f a hole or perforation, g, is formed in the opposite wall of the chamber d, which is thickened at that point. The teat or

stud f fits the perforation of the outer arm, b, of the hanger-frame B, and a bolt, F, pressed inward by a spring-arm, G, through the perforation of the inner arm, a, of said frame, enters the hole or perforation g of the truck-frame, and locks said truck-frame in place, the bolt and the teat or stud thus forming journals, upon which the hanger-frame B may rock from side to side.

By reason of the difference in length of the arms a and b of the frame B, the axis of the teat or stud and of the bolt is inclined relatively to the sole-plate A, which stands in a substantially horizontal plane, thus causing the well-known turning action of the truck-frames when in use.

Thus far the construction is similar to that of my former skate, with the exception of the box or chamber d of the roller-frame. Within said box or chamber is placed a block of rubber or other elastic cushion, H, slightly smaller than the interior of said chamber, as shown in Figs. 2 and 3, and above the box or chamber the hanger B is cut out to give room for a compression-screw, I, and a bearing-plate, J, which are shown in position in Figs. 1, 2, and 3, and detached in Fig. 4. The plate J is transversely serrated to cause it to gain a firm hold upon the rubber and prevent the latter from spreading out and bearing against the ends of the box or chamber d where it would interfere more or less with the rocking action of the frame. The screw I is of large diameter, and its threaded stem or shank h is arranged to screw into a hole or socket, i, in the hanger-frame B above the box or chamber d. The lower end of the screw is enlarged to form a boss or disk, j, which is shown of cylindrical form and provided with cavities or perforations k, but which may be polygonal to receive a wrench or other tool, or provided with lugs or projections for the same purpose. The boss or disk j is formed with a central stud, l, which enters a central hole or seat, m, in the plate J, and its lower face is provided with a series of shallow cavities, n, to receive one or more slight projections, o, formed upon the upper face of the plate J, as shown in Figs. 3 and 4.

The number of cavities and projections may be varied and their arrangement may be reversed; but in every case the projections should be made conical or hemispherical, in

order that they may ride into and out of the cavities with certainty and ease.

The plate J rests directly upon the cushion or spring, and the disk or boss j bears upon 5 the top of the plate J, the plate being retained in proper relative position by the stud l, hence by turning the screw downward the plate will be caused to press more firmly upon the cushion H, and to compress it, thereby causing it 10 to offer greater resistance to the rocking motion of frame B upon the stud f and bolt F, the inner wall of the box or chamber d being raised sufficiently to prevent the turning of the plate with the screw.

15 The elasticity and consequent pressure of cushion H holds the plate J up firmly against the disk or boss j, which latter is made large to give a wide bearing for and prevent the rocking of the plate, and being thus held up 20 the projections o are held in the cavities n, and the screw I is thereby prevented from working back and varying the compression of the cushion. The elasticity of the cushion, however, permits the plate to yield and move 25 downward when any considerable force is applied to turn the screw I, which is conveniently done by inserting a wire or rod into one of the holes k of the boss j and moving it laterally. The beveled or curved faces of the cavities n 30 ride over the projections o and force the plate down, overcoming the resistance of the cushion.

By this construction and arrangement I am 35 enabled readily and accurately to adjust the resistance of the cushion, the boss j of the screw being accessible from the sides of frame B without previous adjustment of any other part, and, if desired, while the skate is fastened upon the shoe of a skater.

40 It will be observed that this construction avoids any change in the inclination of the axis on which the frames B rock, that there is no cutting of the cushion, and that said cushion is prevented from spreading laterally 45 to any considerable extent—a difficulty which has heretofore interfered greatly with the variation of resistance of the cushion.

It is important that the threaded stem be

made to screw into the frame B, instead of employing a fixed stem and a nut or disk 50 screwed thereon, as the plan here described presents no obstacle to the free rise of the rubber when the pressure is diminished, besides being cheaper and easier to make and affording greater range of adjustment. 55

Stop-shoulders p are formed upon one of the arms a or b, against which the truck-frame strikes to limit the rocking motion.

In Figs. 5, 6, and 7 I have shown the box or chamber d as formed with or in the under side 60 of the plate J, the upper face of the truck-frame being in such case serrated instead of the plate. When this construction is adopted, the box is provided with slots q q to permit it to pass down over the journals F f of the truck-frame, and the journal f is shouldered to limit its passage into the eye c. In all other respects the construction will remain as explained.

It is of course understood that one complete 70 hanger and truck-frame with rollers, cushion, and adjusting devices is placed at each end of the sole-plate, as usual.

Various features and details of construction herein shown and described constitute the subject-matter of a separate application filed as a division of the present case on the 24th day of March, 1885, and such features and details for this reason are not claimed herein. 75

Having thus described my invention, what I 80 claim is—

In a roller-skate, the combination, with the sole-plate, of a hanger-frame, a truck-frame pivotally connected therewith, an elastic cushion supported by the truck-frame, and a compression-screw having an enlarged head bearing upon a plate resting upon the upper face of the cushion, and a threaded stem rising from the upper face of said head and seated in a threaded socket in the hanger-frame above 85 90 said head, as and for the purpose set forth.

MICAJAH C. HENLEY.
